UNITED STATES PATENT OFFICE.

JAMES H. JACKSON, OF DETROIT, MICHIGAN.

OIL BURNER.

Application filed July 2, 1927. Serial No. 202,985.

This invention relates to an oil burner, and has for its object an improved organization of parts by means of which a very low grade of oil, even such waste as discarded crank case oil, may be employed for combustion purposes. The construction herein illustrated is of further advantage in that it departs from any reliance upon spraying, which, with the grade of oil indicated, would be a difficult operation, gravity feed alone being necessary to effect the purpose desired.

In the drawings:

Figure 1 is a side elevational view largely in section, showing my improved apparatus in position in a furnace shell.

Figure 2 is an enlarged sectional elevation of the heating or burner plate and its adjacent parts.

Figure 3 is a plan view from above of that portion of the device illustrated in Figure 2.

Figure 4 is a plan view partly in section, taken along the line 4—4 of Figure 1 and looking in the direction of the arrows there shown.

Figure 5 is a plan view from beneath of the undersurface of the burner plate, bringing out the relation of the lugs to it and to the annular shoulder whereon they are designed to rest.

Figure 6 is an elevational view, similar to Figure 1, of a slightly modified form of construction, wherein the appropriate contouring of the lower part of the furnace shell and of the grate bars enables the omission of the air inlet pipe as a separate elemental feature.

A indicates a furnace shell, through the bottom portions of whose wall extends an air inlet pipe B, controlled by a butterfly baffle C. Extending centrally of this pipe, for a portion of its length at least, is the gas supply or pilot pipe D, which, like the air pipe B, terminates at substantially the level of the grate bars F, whose central portion is cut-away for the passage of these pipes therethrough. Resting on the peripheral edge of this cut-away portion of the grate bars is the burner trough G, which consists of a pipe-surrounding collar H and an outer annular portion J, between which is formed the oil trough G, from which waste oil may be drawn through the pipe L. Resting on the top of the inner collar H are a plurality of lugs, as M, which project from the bottom face of the burner plate N, thus

providing an annular space P, whose continuity is interrupted only by the lugs M, through which the burner vapors may pass about the edges of the plate N. As brought out in Figures 1 and 2, the central portion K of the plate N is preferably of turret form, through the sides of which are pierced burner holes O for the further egress of the combustion products induced by the gas pipe D. The top surface of the turret portion K is corrugated or cross-hatched, as shown, to facilitate the flow of oil particles impinging thereon toward the periphery of the burner plate.

Spacedly above the elements thus far described is positioned a cooling air pipe R, which passes through the wall A of the furnace and at its inner end turns downwardly. Supported from this inner end, as by struts S, is a baffle T of inverted truncated conical form, its central portion being apertured as at T' in axial alignment with the down turned inner end of the air pipe R and with the burner plate N and gas pipe D. A sleeve or guiding shell W extends through the hole T' in the baffle, upwardly to above the level of the end of the oil pipe V, and downwardly to just above the level of the top edge of the outer annular wall J of the oil trough member, thus preventing the flames rising from the burner plate from igniting the oil immediately upon its emergence from the end of the oil pipe V. Spacedly positioned centrally of this air pipe R is the oil pipe V, whose downwardly turned end is adapted to discharge oil particles through the sleeve W and the hole T' and onto the turret portion of the burner plate N. The feed through the oil pipe V may be from a superiorly positioned storage or supply source, thus making it a true gravity feed.

The burner plate having first been heated by the action of the flame from the pipe D, the oil supply pipe V is then allowed to commence its dropping of oil particles on the heated top K of the turret portion of the burner plate, and these becoming ignited soon take up the major portion of the heat-delivering function of the burner, receiving the igniting gases both through the aperture P about the peripheral edge of the burner plate N and through the holes O in the sides of the turret. As the flames rise they are confined and forced outwardly and swirlingly by their impingement upon the

inclined surface of the baffle T, and such particles as have not been ignited drop back into the trough constituted by the walls G and H and some are then subsequently ignited, while such others as are not ignited may at the end of the burner's operation be drawn away through the waste pipe L above mentioned.

There is thus produced a very efficient and economical burner construction which functions very satisfactorily, both as regards the completeness of the combustion effected and as regards the avoidance of any spraying action upon the oil particles, thanks to the gravity feed through the oil supply pipe V.

In the modified form of construction shown in Figure 6, in place of the air inlet pipe B and the horizontal grates in the form of construction just described, I provide a preferably conical or outwardly sloping grate X, with suitable holes or spaces Y, through whose center the pilot pipe D passes. In addition, the lower portion of the furnace shell Z is suitably shaped so as to form a funnel similar in function to the air inlet pipe B, the access of air thereto from without being controlled by the damper or door Z'.

What I claim is:

1. In an oil burner, in combination with a gravity-fed supply pipe, a burner plate positioned subjacently thereof onto which the oil particles may fall from said supply pipe, an annular trough member spacedly surrounding said burner plate, means for releasing waste oil particles therefrom, a pilot flame pipe spacedly positioned beneath said burner plate, and an air inlet pipe spacedly surrounding said pilot flame pipe in position to regulatably direct a current of air toward and about said burner plate.

2. In an oil burner, in combination with gravity-fed means for releasing oil in predetermined quantities, a cooling pipe spacedly surrounding the delivery end of said oil pipe, an apertured baffle member positioned in axial alignment with the end of said oil pipe and through which the oil particles released therefrom are adapted to pass by gravity, an oil-confining trough member positioned subjacently of said oil pipe and said baffle member, a burner plate supported by selected portions of said oil trough mem-

ber in axial alignment with the oil supply pipe and said baffle, and means for primarily heating said burner plate and for thereafter deflecting theretowards a supply of air for commingling with the oil particles atomized by contact with said burner plate.

3. An oil burner, having, in combination with a gravity-fed oil delivery pipe, an apertured baffle member positioned therebeneath in axial alignment, a burner plate spacedly subjacent said oil delivery pipe and said baffle member, an annular trough member whereby said burner plate is supported, and means for heating said burner plate and for inducing an upward flow of atmospheric air in the vicinity of said burner plate for commingling with the oil particles deposited thereon and distributed thereby.

4. An oil burner, having, in combination with a subjacent pilot burner and means spacedly engaging thereabout for directing a current of air upwardly, a burner plate and a spacedly encircling oil trough spacedly positioned thereabove, and a gravity-fed oil delivery member positioned above said burner plate in spaced axially aligned relation, and a baffle member spacedly interposed between said burner plate and said oil delivery member, whereby the upwardly rising combustible gases may be given a swirling treatment to facilitate their further commingling.

5. In an oil burner, the combination of an enclosing furnace shell, an oil-delivery pipe projecting interiorly thereof, a cooling air pipe spacedly surrounding said oil delivery pipe, a centrally perforated baffle member positioned beneath said oil delivery pipe in axial alignment therewith, a burner plate positioned spacedly beneath said oil-delivery pipe and said baffle, an annular trough member spacedly surrounding said burner member in position to receive the surplus oil particles initially falling on said burner plate, a gas pilot member positioned beneath said burner plate, and an air inlet pipe whereby a current of air may be upwardly guided adjacent said gas pilot member and said burner plate, for commingling with the oil particles in the vicinity of the latter.

JAMES H. JACKSON.
